UNITED STATES PATENT OFFICE.

JACOB ALPHEUS OVERLANDER, OF NEW YORK, N. Y., AND JESSE LLOYD OVERLANDER,
OF LINCOLN, NEBRASKA.

SCREEN AND HANGER THEREFOR.

1,182,502.

Specification of Letters Patent. Patented May 9, 1916.

Application filed October 31, 1911. Serial No. 657,699.

To all whom it may concern:

Be it known that we, JACOB ALPHEUS OVERLANDER and JESSE LLOYD OVERLANDER, citizens of the United States, residing, respectively, in the city of New York, in the county and State of New York, and in the city of Lincoln, in the county of Lancaster and State of Nebraska, have invented new and useful Improvements in Screens and Hangers Therefor, as appears by the following specification.

The invention relates to improvements in vertical sliding screens for windows commonly used in dwelling houses in summer to prevent incursions of flies and the like.

Among the objects of the invention are the following: a simple means of adjustment of the screen frame independent of window sashes, curtains or shutters, voluntary exit or egress for insects finding lodgment within the house and prevention of ingress and regress of those from without.

The drawings illustrate briefly a practical application of our invention.

Figure 1 is an elevation of the window frame complete with screen, screen frame and hanger properly adjusted. Fig. 2 is a side view of screen, screen frame and hanger detached. Fig. 3 is a cross section of Fig. 1, taken on a line 3—3, showing among other things the screen frame and line of attachment of the screen or wire fabric designated as the screen plane y. Fig. 4 consists of diagrammatic views of the diversified and modified forms of application. Fig. 5 is a detail of one of the offsets or niches in the upright members of the screen frame.

Screen frame D comprises two lateral or upright members and two horizontal members miter-jointed and secured together in the usual manner about a rectangular opening, as shown, which is covered by the wire fabric designated screen plane y, and is properly adjusted to the window frame A inside of the window sashes, see Figs. 1 and 3. The groove or channel 11, Fig. 3, abutting the window frame in the two upright and lower horizontal members is adapted to retain the supporting or suspension cable 5. If preferred, a flexible steel or sheet metal band may replace the cable 5 and with a like effect.

At the respective angles of the window frame and in the groove or channel 11, Fig. 3, screw-eyes 8, Figs. 1 and 2, are entered

through which cable 5 is passed, held in position, as stated, and kept taut by the turn buckle 6. By this means free vertical excursions of the screen frame are provided independent of the window curtains, sashes or shutters and vice versa. The frame D, so constructed, has on each inner margin of the upright members a notch, Fig. 5, positioned directly opposite to and horizontally with each other, having vertical planes outwardly from and substantially parallel with the edges of the upright members and transverse planes intersecting at the outer surface of the frame and diverging as they extend inward and downward. The wire fabric or netting is uniformly attached to the inner surface of the screen frame until the notches are reached, where it is looped or folded back upon itself, Fig. 4, like a lip suspended in front of the pocket formed subsequently by pushing the screen into the notches of the frame before attachment, thus providing a trap in the screen at the pocket. A small space intervenes between the most dependent portion of the fold or loop and the screen of the outer side of the pocket, which tapers downward and inward, as at 4, Fig. 5, to admit of free access thereto. The sides of the pocket opposite the redoubled portion of the screen converge to form a basal angle at the outer surface of the frame, through the apex of which a plurality of holes are serially arranged as exits for the flies. In lieu of the plurality of holes, as suggested, a slotted aperture 2, Fig. 1, either with or without corrugated margins, formed by attaching relatively large and small sections of wire fabric to the screen frame extending outwardly through the offset and terminating at the outer angle 95 thereof, may be substituted.

We may now briefly explain the operation of our improved screen. The curtains are drawn over the window and screen down to the offset, (see Fig. 3). The insects are attracted by and approach the light. They alight upon the screen below the fold thereof at the offset and travel upward thereunder into the trap where they reach the slotted aperture or plurality of holes, as the case 100 may be, through which they escape. Their ingress or regress is made impossible by reason of the angularity of the planes of the wire fabric in the offset approaching the apex at the exit 2.

By the mechanism thus described and shown, we provide a screen that is the simplest possible, most easily constructed and manipulated, as well as the least expensive.

5 What we claim, is:

1. A combination comprising a screen frame, exterior marginal grooves in the members thereof abutting the window frame, a screen or wire-fabric attached to 10 the screen frame, screw eyes, a turn buckle, a supporting band or suspension cable adjusted thereby to said window frame, said suspension cable forming a hanger for said screen frame and means retaining the screen frame in slidable relation with the suspension cable, substantially as shown.
- 15 2. A window screen comprising a substantially rectangular frame of standard thickness with the opposing edges of the upright members similarly notched intermediate 20

their ends, each of said notches having two transverse planes, converging and intersecting at a point coincident with the outer surface of the frame and limited outwardly by a third plane substantially parallel with the 25 edges of the upright members, a screen fabric attached to the inner surface of the frame provided with a looped portion suspended in front of a pocket formed by bending the fabric into the notches and fly-exits in said 30 screen at the base of the pocket.
